UNITED STATES PATENT OFFICE.

A. H. EMERY, OF MEXICO, NEW YORK.

SASH-FASTENER.

Specification of Letters Patent No. 24,450, dated June 21, 1859.

To all whom it may concern:

Be it known that I, A. H. EMERY, civil engineer, of Mexico, county of Oswego, and State of New York, have invented a new, useful, and Improved Window Spring and Sash Fastener; and I do hereby declare that the following is a full and exact description thereof, reference being had to the accompanying drawings, and to letters of reference marked thereon, all of which make a part of this specification.

Like figures represent like parts.

The nature of my invention consists in providing for windows a cheap and durable fastener manufactured from drawn pipe, and constructed in the manner as herein-after described.

To enable others skilled in the art to make and use my invention, I will now proceed to describe its construction, which is as follows, to wit:

Figure 1 shows the entire fastener ready for use, Fig. 2, shows the construction and arrangement of each and every part thereof, 25 in which (a) is the tube containing the coiled spring (f) and the knob rod (c), which rod passes through the end (g) and the end (h) opposite to the end (g). The coiled spring (f) passes around the rod (c), and between the ends (g and h) aforesaid. The tube (a) is made of drawn pipe of any size required. The head or end (g) is put in the tube (a) in the manner as a nut and screw. The end (h) is fitted within the tube (a) and then secured by means of riveting down upon it the end of the tube (a). This tube may be made of any kind of material that will answer the purpose required.

(e) is a socket put into the jamb casing of any window so as to receive the end of the knob rod or bolt (c). Fig. 3, shows the bolt (c), the knob (b). This bolt (c) is constructed in shape from (i to j) as shown at Fig. 4. The hole through the end (g) 40 Fig. 2, is made to correspond and exactly fit this part of the said bolt, so that, when it is drawn back by the knob (b) and entirely from the socket (e) and then turned around one half of its diameter, it will then remain, 45 50 until again moved, by means of a shoulder at (j).

This fastener is put into the stile of the window sash by boring a hole through the same so that the tube of the fastener will perfectly fit the said hole. The knob (b) will be upon the inside of the sash convenient to operate the said fastening bolt (c). This fastener may be used at any place in the sash of windows where it may be 55 60 deemed best and most convenient and effectual.

Having thus described my invention what I claim and desire to secure by Letters Patent, is—

1. The construction of a window sash 65 spring and fastener of drawn pipe with the end (g), and the end (h) arranged and fastened therein as herein described.

2. I, also, claim the construction of the 70 knob rod or bolt (c) as and for the purposes herein described and set forth.

In testimony whereof, I have on this 18th day of April 1859, hereunto set my hand.

A. H. EMERY.
